UNITED STATES PATENT OFFICE.

GEORGE DANIEL KILBERRY, OF WORCESTER, MASSACHUSETTS, ASSIGNOR TO RICE, BARTON & FALES MACHINE & IRON COMPANY, A CORPORATION OF MASSACHUSETTS.

FOURDRINIER MACHINE.

1,147,871.

Specification of Letters Patent. Patented July 27, 1915.

Application filed January 11, 1915. Serial No. 1,579.

To all whom it may concern:

Be it known that I, GEORGE D. KILBERRY, a citizen of the United States, residing at Worcester, in the county of Worcester and 5 State of Massachusetts, have invented a new and useful Fourdrinier Machine, of which the following is a specification.

This invention relates to a Fourdrinier machine in which the ordinary shaking action does not take place.

The principal object of the invention is to provide a practicable and efficient means whereby a great amount of time is saved every time the wire is to be replaced or renewed, and whereby injury to the table rolls is avoided.

The invention also involves supporting devices or sectional tables for the several table rolls which are movable laterally with respect to the whole machine for the purpose of withdrawing these rolls from the side to permit of removal and replacement of the wire; means whereby the movable sections of the table can be accurately located in place 25 when removed and returned; convenient means for introducing the rails on which these sections run, and other features of construction, as will appear.

Reference is to be had to the accompanying drawings in which—

Figures 1 and 2 are side elevations each of a portion of a Fourdrinier machine constructed in accordance with this invention, and Fig. 3 is a sectional view on the line 3—3 35 of Fig. 1 showing one of the sections of the machine in end elevation.

It will be seen that the invention is shown as applied to a Fourdrinier machine of a well known type in which the wire A passes 40 over a series of table rolls B. However, instead of the usual frame-work, this part of the machine is entirely changed in accordance with this invention and for this purpose a bed 10 is provided in one or more sections 45 constituting the supporting means for this part of the machine. On this bed are arranged a series of stands 11, each one being provided with two substantially flat top surfaces 12 (except the end ones and these are 50 provided with one of these only). Located between these two surfaces, or at the side of the surface when only one is present, is a socket 13 formed in the stand. It will be understood that two of these stands are 55 located opposite each other. These sockets

are provided with one or two rails 14, as the case may be. These rails are shown as in the form of channel irons and project up above the top of the stand in position. These are held apart by spacing blocks 15. The 60 top surfaces of these rails constitute tracks for wheels 16. These wheels are arranged on a series of table sections 17 the legs of which normally rest on the surfaces 12. Each of these table sections is designed for supporting a plurality of table rolls B mounted in ball bearings 18^a thereon for this purpose.

The rails 14 are capable of a slight motion up and down in sockets or guides 13 and for this purpose each of the stands is provided with a vertically moving rod or pin 18 having a plate 19 on the top for supporting the bottoms of the rails 14. On the base 10 is provided a cam 20 for each of these pins 70 18, arranged in position to engage the bottom of the pin and raise it when the cam is turned on its axis by means of a handle 21. The table sections 17 are provided with pins 22 for entering holes in the surfaces 12 for 80 locating the table sections in proper position. For supporting the table sections when withdrawn from the machine rails 24 are provided similar to the rails 14. One of each is arranged to rest in one of the sections and the other has a support 23.

In order to provide conveniently for the introduction of the heavy rails 14 whenever the endless wire is to be replaced, the following mechanism is shown: Mounted to swing 90 on the axes of studs 25^a, are a series of frames 25, one located at each end of each pair of rails and having rollers 26 on their ends. These are capable of swinging around to the position shown in Fig. 3, for the purpose of supporting the rails at a distance from their ends while being introduced into the machine. After the rails are introduced, frames 25 are swung out to one side, as shown in Fig. 1 to get them out of the way.

The drawings show the usual deckle strap 27 and wash trough 28 for it. The frame 29 for the wash trough is supported by one of the table sections. Although I have not shown the entire machine, it will be understood that the breast roll 30 is also mounted on one of these table sections and moves out with it, the operation being the same as that described above, but the track is raised by a screw 31.

The operation of moving the tables so as to supply or replace a wire will be understood from what has been said, the wire being let down at the bottom by slackening 5 up the adjusting drums as 32 so as to form loops that pass below the level of the surfaces 12. The rails 14 are raised and the several table sections drawn out on the rails 24 which are in place. The wire is then 10 placed readily with practically no difficulty, it being supported by the usual rolls or cylinders not shown herein. Then before it is tightened up and while its parts form loops below the level of the surfaces 12 the table 15 sections are moved in by hand. When the pins 22 register with their perforations in the tops of the stands these pins are allowed to drop into these perforations and the pins 18 are lowered by turning the handles 21. 20 This brings the bottoms of the tables down on the surfaces 12 and relieves the wheels of their weight. The rails are then removed and preferably the rails 14 are withdrawn and laid aside until needed again. 25 The wire is tightened by the usual adjusting drums. In this way a very material saving in time and cost is accomplished every time the wire former has to be renewed and this is an important result in 30 this class of machines because a very material loss of time has been necessary heretofore. Another important advantage lies in the fact that by this arrangement, a section of rolls are removed together without 35 taking them out of their bearings. Consequently, all the usual injury to them and their journals is absolutely avoided.

Although I have illustrated and described only a single embodiment of the invention, I am aware of the fact that many 40 modifications can be made therein by any person skilled in the art without departing from the scope of the invention as expressed in the claims. Therefore, I do not 45 wish to be limited to all the details of construction herein shown and described, but

What I do claim is:—

1. In a Fourdrinier machine, the combination of a framework, rails supported 50 thereby under the top thereof, a frame pivoted adjacent to said rails on an upright

axis, and an anti-friction means on said frame adapted to assist in supporting a rail when the frame is swung inwardly.

2. In a Fourdrinier machine, the combination with a frame having a plurality of supporting surfaces, table sections for supporting rolls normally resting on said surfaces, said table sections being provided with wheels, transverse rails extending 60 across said frame under the wheels, and means for raising said rails for engaging the wheels and lifting the table off said supporting surfaces.

3. In a Fourdrinier machine, the combination with a series of stands located opposite each other on the side of the machine, each stand having a supporting surface at the top, a plurality of table sections having legs by which they are adapted to be 70 supported on said surfaces and adapted to carry table rolls, and means whereby they can be withdrawn from position laterally without contacting with said surfaces.

4. In a Fourdrinier machine, the combination of a frame having oppositely located sockets therein, a rail supported in two of the opposite sockets and movable up and down therein, a pair of pins for carrying said rails, and cams for raising said pins 80 and rail.

5. In a Fourdrinier machine, the combination of a frame having sockets located oppositely for supporting rails, a frame pivoted adjacent to one of said sockets on an upright axis, and a wheel on the frame adapted to assist in supporting the tracks when the frame is swung inwardly.

6. In a Fourdrinier machine, the combination of a base, transverse rails removably 90 mounted thereon, sectional tables for supporting rolls adapted to move on said rails, and additional rails placed at the ends of the first named rails, for receiving the tables at one side of the machine.

In testimony whereof I have hereunto set my hand, in the presence of two subscribing witnesses.

GEORGE DANIEL KILBERRY.
